UNITED STATES PATENT OFFICE

93,023

DESIGN FOR AN ASH RECEIVER

Adolph Keller, St. Louis, Mo.

Application April 25, 1934, Serial No. 51,515

Term of patent 3½ years

To all whom it may concern:

Be it known that I, ADOLPH KELLER, a citizen of the Republic of Germany, residing at St. Louis, State of Missouri, have invented a new, original, and ornamental Design for an Ash Receiver, of which the following is a specification, reference being had to the accompanying drawing, forming a part thereof.

In the drawing:
Figure 1 is a top plan view.

Figure 2 is a side elevational view, and Figure 3 is a sectional view taken on the line 3—3 of Figure 1 of an ash receiver showing my new design.

I claim: The ornamental design for an ash receiver, substantially as shown.

ADOLPH KELLER.
